DIAMOND TOOL ASSEMBLY

Joseph Loecy, Jr., Euclid, Ohio

Application July 14, 1950, Serial No. 173,751

5 Claims. (Cl. 125—11)

1

The present invention relates to the art of diamond tools for dressing grinding wheels and is an improvement upon the device disclosed in my co-pending application Serial No. 62,449, filed November 29, 1948, as well as that disclosed in my co-pending application Serial No. 134,964, filed December 24, 1949.

According to the regular practice, as more fully explained in the above-noted applications, a diamond tool is adapted to be moved at intervals into position for operative engagement with a grinding wheel for dressing the same; and, in order to always present a new sharp point and to prevent the diamond from wearing unevenly, the workman has heretofore been depended upon to turn the diamond tool. But experience has shown that the workman can not be depended upon always to make these adjustments when required and to the proper degree.

Therefore, in the present application as in those above noted, the object is to devise an assembly in which the diamond tool may be turned slightly by combined hydraulic and mechanical means so as to always present a new sharp point of the diamond to the wheel and thus prevent uneven wear of the diamond.

A more specific object is to provide such a device with means for producing the desired degree of rotary adjustment of the diamond point with a comparatively small longitudinal clearance of the adjusting means therefor.

Another specific object of my present form of invention is to provide an improved and positive form of means for ensuring adjustment of the diamond tool in only one direction rotatably about the longitudinal axis thereof.

Other objects will appear from the following description when considered together with the accompanying drawing and claims.

Fig. 1 is an elevation of a complete unit which embodies my present invention;

Fig. 2 is a longitudinal sectional view of the forward end portion thereof;

Fig. 3 is a sectional view taken on line 3—3 of Fig. 2; and

Fig. 4 is a sectional view taken on line 4—4 of Fig. 2.

It is to be understood that the present form of disclosure is merely for the purpose of illustration and that there might be various modifications thereof without departing from the spirit of my invention as herein set forth and claimed.

My present assembly may be mounted upon or attached to any type of grinder; for instance, the spindle shaft S of the dresser barrel B of

2

such a machine may have this device mounted thereupon in the manner indicated in Figs. 1 and 2 of the present drawing. My present device is of such design as to be of substantially the same cross sectional diameter and form as the dresser barrel B so as to constitute virtually a continuation thereof in form and appearance. This arrangement has also a decided mechanical advantage with respect to the positioning of the 10 tubular ducts for the hydraulic fluid, as will be understood.

The turner body 1, which is mounted upon the spindle shaft S, has provided within the outer end thereof the plunger 2 which is adapted for 15 limited straight-line movement therewithin, there being suitable space allowed with respect to the fixed end cap 3, and the annular wall of the plunger 2 being provided with suitable clearance for such movement. The plunger 2 may 20 be so mounted as to have its longitudinal axis at an angle to that of the body 1.

Extending radially inwardly from the cylindrical wall of the recess at the forward end of the body 1, there is provided the fixed pin 4 25 which has co-operative engagement within the inclined slot 5 in the outer surface of the plunger 2; in fact, the outer surface of the plunger 2 may be provided with a plurality of such slots at as many different angles so that any one of them may be employed in connection with the pin 4 according to the degree of turning movement of the plunger 2 that is desired for a given longitudinal movement thereof.

The pin 6, which extends radially inwardly 30 from the inner surface of the plunger 2, has operative engagement within the slot 7 which is provided in the outer surface of the annular transmitting ring 8 and which is inclined in the opposite direction from that of the slot or slots 5 so as to amplify the rotary movement of the ring 8.

The inner surface of the ring 8 is adapted to have one-way locking engagement with the enlarged cylindrical rear end portion 9 of the tool holder 10 which has the tool 11 screwed into the 45 forward end thereof, with the diamond point 12 at the outer end of the tool 11. This locking engagement may consist of the spring-pressed pins 13 which are arranged within the recesses 50 14 in the periphery of the enlarged portion 9 and which are adapted to have one-way binding engagement in the wedge-shaped spaces provided between the walls of their notches and the inner surface of the ring member 8, after the manner of a one-way clutch. The coil springs for the

pins 13 are indicated at 13a and are seated in wells in the rear walls of the recesses 14.

Rotary movement of the plunger 2 and the ring member 8 in one direction will, by virtue of the one-way clutch means, carry the tool-holder 10 therewith as part of the unitary assembly; but, when the plunger 2 and ring member 8 have rotary movement in the opposite direction, the clutch means will not be effective and the plunger and ring member 8 will turn alone and without turning the tool holder 10. In the present form of illustration, forward movement of the plunger 2 and ring member 8 will result in rotary movement of the same and also of the tool holder 10, but the plunger 2 and ring member 8 in their rearward movement will not cause any turning movement of the tool holder 10. As a result, the tool holder and its diamond point will be turned in only one direction and there will always be ensured a fresh portion of the diamond point for the dressing operation.

Within the chamber provided within the main plunger 2, there is provided what may be termed a back-stop 15 which has a circular disk portion of less diameter than that of the chamber therefor and which has a stem portion 15a extending rearwardly out through the rear wall of the main plunger 2. Suitable sealing means 15b surrounds the stem 15a, and suitable sealing means are provided also about the tool holder 10 and about the main plunger 2, as indicated by reference numerals 10a and 2a, respectively.

Hydraulic fluid may be supplied to the rear end of the main plunger 2 through the tube or duct 16 provided within the turner body 1 and extending through the dresser barrel B; and likewise, the hydraulic fluid may be supplied to the forward end of the main plunger 2 through the tubular passage 17 in the turner body and extending through the dresser barrel B. Cooling fluid may be supplied through tube 18 to the point of dressing. The tubes 16 and 17 are connected to a suitable control valve like that shown in the above-noted co-pending application Serial No. 134,964, to which reference may be had for a fuller understanding with respect to this feature. Suffice to say, when the valve is set in one position, the hydraulic fluid may be applied to the rear end of the main plunger 2 through the duct 16 so as to move the plunger forwardly while the fluid fills the space at the rear thereof and while the fluid at the forward end of the main plunger is forced out through the tubular passage 17 and through the valve to the reservoir for the hydraulic fluid in the same manner as more fully explained in the above-noted co-pending applications. Then, when the valve is set in its other position, the reverse flow of the hydraulic fluid will take place; that is, it will be applied through duct 17 to the front end of the main plunger 2 so as to force the same rearwardly and, at the same time, the fluid at the rear of the main plunger will be forced out through the tubular passage 16 and the valve to the reservoir. It might be explained that there is sufficient clearance between the inner surface of the main plunger 2 and the outer surface of the ring 8 to permit the hydraulic fluid to pass therebetween, during rearward movement of the main plunger, and to fill the space within the main plunger to the rear of the disk portion 15 of the back-stop which remains stationary during the movements of the main plunger; and the pressure of the hydraulic fluid within this space will serve to ensure that the member 15 will be maintained

in the position indicated in Fig. 2 of the drawing so as to hold the enlarged portion 9 against the fixed end cap 3, as seen in Fig. 2. Here it might be pointed out that the ring 8 and tool holder 10 have only turning movement about the longitudinal axis and do not have longitudinal movement therealong. Slight clearance may be provided at the forward end of ring 8 so as to ensure against the same sticking. My present improved device may be mounted for movement laterally into and out of engagement with the work.

As above explained, the forward movement of the main plunger 2 by the hydraulic fluid is converted into a turning movement thereof by virtue of the pin and slot mechanism, with the result that the main plunger 2 has a spiral movement about the longitudinal axis of the device. Such movement of the main plunger will, by virtue of the pin and slot connection with the ring 8, cause an amplified turning movement thereof; and, with this arrangement, there may be obtained the desired degree of turning movement of the ring 8 with a comparatively short longitudinal movement of the main plunger. As also explained above, the turning of the ring 8 will effect locking engagement thereof with the tool holder and these two parts will turn together as a unit so as to adjust rotatably the position of the tool holder and the diamond point carried thereby. When the tool holder has been rotatably adjusted in the manner explained, it will be effectively held in such position by the pressure of the hydraulic fluid which will hold the enlarged portion 9 of the tool holder against the end cap 3. To repeat, such turning of the tool holder takes place only during the movement of the main plunger 2 in one direction thereof, in the forward direction according to the present form of illustration, by virtue of the particular arrangement of the one-way clutch engaging means between the ring 8 and the tool holder 10. Whereas such engagement is effective during movement of the main plunger 2 in its one direction, there will be free relative movement between the tool holder 10 and the ring 8 during the movement of the main plunger 2 in the opposite direction.

Notable among the practical advantages of the present form of device is the positive and dependable character of the automatically effected operation of the means for producing the turning movement of the tool holder in only one direction, that is during the movement of the main plunger in only one direction, and with a relatively short extent of such longitudinal movement of the main plunger. Furthermore, the entire mechanism is of comparatively simple and compact form and is capable of operation in an efficient and dependable manner as has already been demonstrated by actual use of this device in the trade.

What I claim is:

1. In a device of the class described, the combination of a cylinder, a plunger within said cylinder and reciprocatable therewith, means including hydraulic means connected to said cylinder for effecting such reciprocatable movement of said plunger pin and inclined slot means operatively arranged between said cylinder and plunger for converting the forward and rearward movement of said plunger into rotary movement thereof, an annular ring within said plunger and having pin and inclined slot means of connection with said plunger for amplifying the rotary movement of said annular ring by said plunger, a tool

holder within said annular ring, and one-way means of clutch connection between said annular ring and said tool holder for transmitting to said tool holder said amplified rotary movement of said ring in only one direction thereof.

2. In a device of the class described, the combination of a cylinder with an inwardly extending front end cap portion, a plunger within said cylinder and reciprocatable therewithin, a tool holder extending through said inwardly extending forward end cap portion and having an enlarged rear end portion located within said plunger with lateral clearance between said tool holder and said plunger, the enlarged rear end of said tool holder being spaced from the rear wall of said plunger and having its front end adapted for engagement with the said cap portion, means connected to said cylinder for moving said plunger forwardly or rearwardly, means of operative connection between said cylinder and plunger for automatically converting the forward and rearward movement of said plunger into rotary movement thereof, and means of operative connection between said plunger and tool holder for transmitting to said tool holder the rotary movement of said plunger in only one direction.

3. In a device of the class described, the combination of a cylinder, a plunger reciprocatable within said cylinder, operating means for said plunger including hydraulic pressure means connected to said cylinder for effecting straight-line movement of said plunger and including also means of operative connection between said plunger and cylinder for converting the straight-line movement of said plunger into rotary movement of said plunger, a tool holder, and means of operative connection between said plunger and tool holder including means for transmitting to said tool holder an amplified turning movement in only one direction thereof.

4. In a device of the class described, the combination of a cylinder, a plunger within said cyl-

inder and reciprocatable therewithin, hydraulic means connected to said cylinder for moving said plunger forwardly and rearwardly, means of operative connection between said cylinder and plunger for automatically converting the forward and rearward movements of said plunger into rotary movement of said plunger, a tool holder, and means of operative connection between said plunger and tool holder including means for transmitting from said plunger to said tool holder an amplified turning movement in only one direction thereof.

5. In a device of the class described, the combination of a cylinder, a plunger within said cylinder and reciprocatable therewithin, hydraulic means connected to said cylinder for moving said plunger forwardly and rearwardly, means of operative connection between said cylinder and plunger for automatically converting the forward and rearward movement of said plunger into rotary movement of said plunger, an annular ring within said plunger and having pin and inclined slot connection therewith for amplifying the turning movement of said ring, a tool holder, and means of operative connection between said plunger and tool holder including one-way clutch connection between said ring and said tool holder for transmitting to said tool holder said amplified rotary movement of said annular ring in only one direction thereof.
